United States Patent Office.

GEORGE STEINEGGER, OF HIGHLAND, ILLINOIS.

Letters Patent No. 75,069, dated March 3, 1868.

IMPROVEMENT IN GANG-PLoughS.

The Schedule referred to in these Letters Patent and making part of the same.

TO ALL WHOM IT MAY CONCERN:

Be it known that I, GEORGE STEINEGGER, of Highland, in the county of Madison, and State of Illinois, have invented new and useful Improvements in Gang-Ploughs; and I do hereby declare that the following is a full, clear, and exact description thereof, which will enable those skilled in the art to make and use the same, reference being had to the accompanying drawings, forming part of this specification, in which—

Figure 1 is a sectional side view of my improved plough, through the line *x x*, fig. 2.

Figure 2 is a plan view of the plough below the section *y y*, fig. 1.

Similar letters of reference indicate corresponding parts.

This invention consists in the arrangement of certain parts of a gang-plough, as will hereinafter be more fully set forth.

In the drawings, the axle *A* is mounted in the usual manner. *B B'* are the swinging beams, to which are attached the ploughs *P* by the clips *a*, as shown. The ploughs are thus permitted to be wholly or partially out of the soil, by the lifting-lever *b*, which vibrates on the end of the fulcrum-brace *d*. These levers are provided with a plate, *e*, which catches into the notches of the rack *f*, affixed to the uprights *g*, and thereby hold the plough at any point of elevation. A rod or link, *h*, connects the lifting-levers with the swinging beams *B B'*. These latter are attached to the axle *A*, by means of eye-plates *i*, bolted to the under side of the beams, the eye of the said plates being connected with the eye-bolts *k* in the axle, as shown. Lateral braces, *l*, similarly connected with the axle, and bolted to the sides of the beams, relieve the eye-plates *i* and eye-bolts *k* from lateral strain. The link *h* is made with two or more holes, for the purpose of adjusting the lever to raise the ploughs higher or lower, as occasion may require. A cross-rod, *m*, connects the two fulcrum-braces, thereby conferring stiffness to them. Brace-rods *n* also assist to render them more secure in their position. The position of the driver on the seat *D* enables him to operate the lifting-levers at will, by pressing upon them with his feet.

This plough is cheap, durable, and has been proven by practical trials to be superior to those gang-ploughs heretofore made, in several important particulars.

I am aware that gang-ploughs capable of being lifted by the driver have been made, and do not claim the lifting of such ploughs broadly.

What I claim as new, and desire to secure by Letters Patent, is—

The swinging beams *B B'*, when lifted by the lever *b* and link *h*, substantially as shown and described, in combination with the lateral braces *l*, eye-plates *i*, and bolts *k*, or their equivalent, all as and for the purpose set forth.
